UNITED STATES PATENT OFFICE.

ABRAHAM A. BROWN, OF NEW YORK, N. Y., ASSIGNOR TO A. L. PALMER CO., OF NEW YORK, N. Y., A CORPORATION.

WAISTBAND-LINING FOR TROUSERS.

1,089,315.

Specification of Letters Patent.

Patented Mar. 3, 1914.

Application filed June 24, 1913. Serial No. 775,469.

To all whom it may concern:

Be it known that I, ABRAHAM A. BROWN, a subject of the Czar of Russia, and a resident of the city of New York, borough of Brooklyn, in the county of Kings and State of New York, have invented a new and Improved Waistband-Lining for Trousers, of which the following is a full, clear, and exact description.

At the present time the linings for the waists of trousers are sewed to the garments by hand. This is objectionable for various reasons. In the first place it necessitates each manufacturer placing out the work among large numbers of seamstresses who do the work at their homes, often in unsanitary environments. This method of distributing the work entails a more or less complicated system of accounts and places the manufacturers under the dependence of a class of help that is largely unreliable, and, furthermore, the price per garment for the sewing in of the waistband linings is considerable, considering the nature of the work.

The object of the present invention is to overcome these difficulties by sewing linings to trousers entirely by machine, thus doing away with the necessity of placing the work outside the factory, in numerous homes, as is now the custom, as the work can be done entirely in the factory at a greatly reduced cost. These advantages accrue from a novel construction of waistband lining which can be easily and quickly made and attached to the garment and at the same time present a neater appearance than do the waistbands which have heretofore been sewed to the trousers by hand.

With these objects in view, and others as will appear as the description proceeds, the invention comprises various novel features of construction and arrangement of parts which will be more fully described herein-after and set forth with particularity in the claims appended hereto.

In the accompanying drawings, which illustrate one embodiment of the invention, and wherein similar reference characters are employed to designate corresponding parts throughout the several views, Figure 1 is a perspective view of the waist portion of a pair of trousers with the improved waistband lining applied thereto, a portion of the lining being broken away to illustrate

the details of construction; Fig. 2 is a perspective view of one section of the lining before the same is completely folded, a portion of the said section being broken away; Fig. 3 is a detail sectional view showing the first step in attaching the lining to the waist portion of the trousers; Fig. 4 is a similar view showing the next step of securing the lining; Fig. 5 is a view showing the lining in its final condition; and Fig. 6 is a fragmentary perspective view of a slightly modified form of lining before the same is applied.

Referring to the drawing, A designates the upper portion of a pair of trousers which is provided with a waistband lining B which is preferably made in two sections 1 and 1^a in the usual manner, each section extending from the middle of the back to the front of the trousers. Each section of the waistband consists, as shown in Fig. 2, of a strip 2 of stiffening material, such as buckram or the like, which gives stiffness to the waistband of the trousers, this strip being of any desired width; and attached to the buckram reinforce 2 is a strip of lining material 3 which has one edge overlying one edge of the buckram strip and secured thereto by a row of stitching 4, as shown in Fig. 2.

The major portion of the lining material 3 extends beyond the buckram strip 2 and is folded on longitudinal lines 5, 6 and 7 in such a manner that the parts 8, 9 and 10 will constitute a compound or zigzag fold, as clearly shown in Fig. 3. The edge 11 of the portion 10 of the lining projects beyond the edge 12 of the buckram when the lining strip 3 is folded, and this edge 11 is presented to the edge 12^a of the trousers A, and the lining is stitched to the latter by a row of stitching 13, Fig. 3, the lining being on the outside of the trousers. The lining is next turned inwardly to a position within the trousers by folding the edge of the trousers just below the seam formed by the stitching 13 until the lining is in the position shown in Fig. 4. The fastening of the lining at the top edge by the stitches 13 is not sufficient to bind the lining in place and therefore a second row of stitching 14 is employed to secure the lower portion of the lining to the trousers. This row of stitching is located in the portion 9 of the lining material close to the line of fold 6, Fig. 2, and in order to do this the flap formed by the

stitching 13 until the lining is in the position shown in Fig. 4. The fastening of the lining at the top edge by the stitches 13 is not sufficient to bind the lining in place and therefore a second row of stitching 14 is employed to secure the lower portion of the lining to the trousers. This row of stitching is located in the portion 9 of the lining material close to the line of fold 6, Fig. 2, and in order to do this the flap formed by the

parts 9 and 10 is turned upwardly, as shown in Fig. 4, to allow the sewing machine to place the stitching correctly. The stitches 14 pass completely through the lining material 3, reinforce or buckram strip 2 and body of the trousers A, the row of stitches being seen on the outside of the trousers, as shown in Fig. 1, but concealed from the inside by being covered by the flap formed by the folded portions 9 and 10 of the lining material, as it will be understood that this flap will be folded down from the position shown in Fig. 4 to that shown in Fig. 5 after the row of stitching 14 is made.

15 It is to be understood that the row of stitching 13 by which the lining is first attached to the garment is made by a sewing machine, but this row of stitching is completely concealed by the turning of the lining from the position shown in Fig. 3 to that shown in Fig. 4, so that from the inside of the trousers no stitching securing the lining in place is revealed.

In Fig. 2 the lining material 3 is shown as one piece, but it is to be understood that it can be made of two pieces 3^a and 3^b, as shown in Fig. 6, joined together at 3^c by a row of stitching 3^d after a piece 3^b has been first sewed to the buckram strip 2 by a row of stitching 3^e.

From the foregoing description taken in connection with the accompanying drawings, the advantages of the construction and method of operation and of the device shown will be readily understood by those skilled in the art to which the invention appertains, and while I have described the principle of operation, together with the device which I now consider to be the best embodiment thereof, I desire to have it understood that the device shown is merely illustrative, and

that such changes may be made when desired as are within the scope of the appended claims.

Having thus described my invention, I claim as new and desire to secure by Letters Patent:

1. A trouser band lining comprising a stiffening strip and a lacing or facing strip completely covering the face of the stiffening strip, the lining strip having its lower edge turned under the corresponding edge of the stiffening strip and its other edge free from and extending beyond the opposite edge of the stiffening strip to form an extension adapted to be sewed to the trousers, and a hanging plait provided in the lining strip midway of its edges and adapted to fold over and cover a row of stitching passing through the lining and stiffening strips and trousers.

2. The combination of a waist portion of a pair of trousers, a lining strip having one edge secured to the trousers and turned inwardly, a stiffening strip disposed under the lining strip and completely covered thereby and having its lower edge enveloped by the lining strip, and a horizontal row of stitching passing through the lining substantially midway between its upper and lower edges and through the trousers, said lining strip being formed with a longitudinal flap or plait integral therewith and hanging down over the said stitching to cover the same.

In testimony whereof I have signed my name to this specification in the presence of two subscribing witnesses.

ABRAHAM A. BROWN.
